DESIGN FOR A FOLDING CHAIR OR SIMILAR ARTICLE

Joseph B. Platt, New York, N. Y.

Application December 14, 1944, Serial No. 116,893

Term of patent 14 years

(Cl. D15—1)

To all whom it may concern:

Be it known that I, Joseph B. Platt, a citizen of the United States of America, residing in New York city, county of New York, and State of New York, have invented a new, original, and ornamental Design for a Folding Chair or Similar Article, of which the following is a specification, reference being had to the accompanying drawing, forming part thereof, wherein,

Figure 1 is a front perspective view of a folding chair or similar article showing my new design.

I claim:

The ornamental design for a folding chair or similar article, substantially as shown.

JOSEPH B. PLATT.
